UNITED STATES PATENT OFFICE.

JOHN D. MCFARLAND, OF ST. LOUIS, MISSOURI.

SURGICAL SWAB.

1,315,026.

Specification of Letters Patent.

Patented Sept. 2, 1919.

Application filed April 14, 1919. Serial No. 289,996.

To all whom it may concern:

Be it known that I, JOHN D. MCFARLAND, a citizen of the United States of America, residing at the city of St. Louis, State of Missouri, United States of America, have invented a certain new and useful Surgical Swab, of which the following is such a full, clear, and exact description as will enable any one skilled in the art to which it appertains to make and use the same, reference being had to the accompanying drawing, forming part of this specification.

My invention relates to a surgical swab and more particularly to that class of swabs in which the swab itself serves as a receptacle or container for the medicament to be applied.

Surgical swabs of the class above referred to have heretofore been made by inclosing the medicament in a glass tube which is sealed by fusion and drawn out into a frangible neck. The absorbent material or swab proper being permanently attached to the container and surrounding the frangible neck which is broken off in order to allow the escape of the medicament into the absorbent material. The objections to such swabs are two fold. First, the breaking of the frangible neck is likely to form splinters of glass which will work through the absorbent material and enter the wound treated. Second, such swabs can be only used once. The object of my invention is to provide a swab which will overcome both these difficulties.

In the accompanying drawings which illustrate one form of surgical swab made in accordance with my invention, Figure 1 is a side view showing the swab proper in position. Fig. 2 is a view similar to Fig. 1, but showing the swab proper replaced by a cap or seal. Fig. 3 is an enlarged sectional view, and Fig. 4 is a plan view of the blank from which the swab holder is formed.

5 indicates the receptacle or container for the medicament to be applied which medicament is preferably an antiseptic such for instance as tincture of iodin. The receptacle is formed of glass and is provided with a neck 6 which is externally threaded and has formed in it a discharge passage 7. When the swab is not in use, this discharge passage 7 is adapted to be sealed by an internally threaded cap 8 as shown in Fig. 2. 55 The outer end of the neck 6 is beveled as indicated at 9, Figs. 1 and 3. This beveled

portion of the neck is adapted to be engaged by the inner non-threaded edge of an annular member 10 which member is provided with arms 11 carrying at their outer ends 60 wings 12 adapted to clamp a tuft 13 of absorbent material such, for instance, as surgical gauze, intermediate of its length so as to divide it into an outwardly extending medicament applying portion and an inwardly extending portion held over the orifice of the discharge passage 7 to receive the medicament.

When the device is not in use, the discharge passage 7 is sealed by the cap 8. 70 When it is desired to use the device the cap 8 is replaced by the annular member 10 which can be engaged with the beveled end of the neck 6 by a slight turning movement. The swab proper is thus held in position to 75 receive the medicament from the container 5. After the device has been used, the swab proper can be removed and the receptacle again sealed by the cap 8.

Having fully described my invention, what 80 I claim as new and desire to secure by Letters Patent of the United States is:

1. The combination with a receptacle for a medicament provided with a discharge opening, of a removable seal for said opening, a holder interchangeable with said seal, and a swab of absorbent material carried by said holder.

2. The combination with a receptacle for a medicament provided with a threaded 90 portion having formed therein a discharge passage, of a threaded seal for closing said passage, and a swab interchangeable with said seal, said swab comprising a holder adapted to engage with the threaded portion 95 of the receptacle, and a tuft of absorbent material carried by said holder.

3. The combination with a receptacle for a medicament provided with a threaded portion having formed therein a discharge passage, of a threaded seal for closing said passage, and a swab interchangeable with said seal, said swab comprising a non-threaded holder adapted to engage with the threaded portion of the receptacle, and a 100 tuft of absorbent material carried by said holder.

4. The combination with a receptacle for a medicament provided with a threaded portion terminating in a beveled end and having formed therein a discharge passage, of a threaded cap for closing said passage, and 110

a swab interchangeable with said cap, said swab comprising a non-threaded holder adapted to engage with the threaded portion of the receptacle, and a tuft of absorbent material carried by said holder.

5. The combination with a receptacle for a medicament provided with a discharge opening, of a swab adapted to be applied to said receptacle, said swab comprising an 10 annular member, arms carried by said annular member, and a tuft of absorbent material clamped between said arms.

15. The combination with a receptacle for a medicament provided with a portion having a discharge passage therein, a cap for said passage engaging with said part, and a swab interchangeable with said cap, said swab comprising an annular member, arms carried by said annular member, and a tuft of absorbent 20 material clamped between said arms.

25. The combination with a receptacle for a medicament provided with a portion having a discharge passage therein, a seal for said passage, and a swab interchangeable with said seal, said swab comprising an annular member, arms carried by said annular member, and a tuft of absorbent material clamped between said arms, said tuft 30 comprising a medicament applying portion extending beyond the arms, and a medicament receiving portion situated between the arms and the end of the discharge passage.

35. The combination with a receptacle for a medicament provided with a discharge opening, of a swab adapted to be applied

to the receptacle, said swab comprising a tuft of absorbent material, and a holder clamping said tuft intermediate of its length and holding the inner end thereof over the 40 discharge opening.

9. The combination with a receptacle for a medicament provided with a threaded portion having a discharge passage therein, a cap for the discharge passage, and a swab 45 interchangeable with said cap, said swab comprising a non-threaded annular member adapted to engage with said threaded portion, arms carried by said annular member, and a tuft of absorbent material clamped 50 between said arms, said tuft comprising a medicament applying part extending beyond the arms and a medicament receiving portion situated between the arms and the end of the discharge passage.

55. 10. A swab for applying antiseptics or the like comprising an annular member provided with an aperture for attaching it to a holder, arms carried by said annular member, and a tuft of absorbent material clamped between said arms.

11. A swab for applying antiseptics or the like comprising an annular member of sheet metal provided with an aperture for attaching it to a holder, a pair of arms 65 formed integral with said annular member and bent out of the plane thereof, and a tuft of absorbent material clamped between said arms.

In testimony whereof, I have hereunto 70 set my hand and affixed my seal.

JOHN D. McFARLAND. [L. S.]
